Primary Examiner — T. Chase Nelson*(74) Attorney, Agent, or Firm* — Banner & Witcoff, Ltd.(57) **CLAIM**

The ornamental design for a shoe outsole, as shown and described.

DESCRIPTION

FIG. 1 is a front perspective view of a shoe outsole showing my new design;

FIG. 2 is a plan view thereof; and,

FIG. 3 is a rear perspective view thereof.

The broken lines showing the remainder of the shoe are for environmental purposes only and form no part of the claimed design.
